UNITED STATES PATENT OFFICE.

HERMAN C. WELTER, OF ROCHESTER, NEW YORK, ASSIGNOR TO HALL-WELTER CO., INC., OF ROCHESTER, NEW YORK.

SUBINKING PRINTING MEANS.

1,174,643.

Specification of Letters Patent.

Patented Mar. 7, 1916.

Application filed December 22, 1915. Serial No. 68,236.

To all whom it may concern:

Be it known that I, HERMAN C. WELTER, a citizen of the United States, residing at Rochester, in the county of Monroe and State of New York, have invented a new and Improved Subinking Printing Means, of which the following is a specification.

My invention relates to printing mechanism and especially to that class embodying machines known as check writers and check protectors. In machines of this character, there have been provided various ways of having the coöperating printing members not only print certain selected characters on a check, or other negotiable instrument, but in so doing to break the paper throughout the printed surface in a manner that ink from the type will be absorbed by the disrupted fibers, the purpose of such mutilation being also to prevent erasure of the printed characters which cannot be effected without tearing the paper.

Heretofore, the construction and operation of the printing mechanism has been such that ink is applied from the type to the face only of the instrument being printed; and it is the object of this invention to provide a platen or die member adapted to co-operate with the type whereby, in forming characters by an embossing or punching operation, ink will be applied to such characters on both sides of the paper, and at the same time there will be a disruption of the fibers.

Another object of the invention is to supply ink to the sub-inking means from the type characters when coming in contact therewith during the printing operation; and a still further object is, preferably, to make the type characters the cutting means and to so relatively conform the die member thereto that the action in disruption of the fibers is more of a tear than a clean cut.

In accomplishing my invention, I make use of a plate, or die member, having a plurality of openings therethrough in the form, preferably, of a series of parallel slots through which projecting portions of type characters are adapted to engage, there being provided, of course, suitable adjusting means to keep such projections and openings in proper registration. The type characters are carried by a support which is movable to bring a predetermined line of type opposite the die and the two members are mov-

able relatively toward and into engagement with each other for the printing operation.

Beneath the die plate and in engagement with the underside thereof is an ink pad against which the underside of the paper is forced by projecting portions of the type characters, thus causing the paper to be inked on the under and embossed side while the impressions made in the face side of the paper by the type characters are inked therefrom. The type is inked by any suitable means which, when the support therefor comprises a type cylinder, is usually one or more ink rollers removably held in yielding contact therewith. The pad is suitably inked before being inserted to place but cannot become dry, as sufficient ink to keep it in proper condition is supplied thereto from the edges of the type characters which contact therewith when cutting through the paper of the instrument being printed.

The accompanying drawings illustrating my invention are as follows:

Figure 1 is a plan view of the sub-inking die member; Fig. 2, a longitudinal sectional view thereof taken along the line $x-y$ of Fig. 1; Fig. 3, a transverse sectional view taken along the line x^1-y^1 of Fig. 1; Fig. 4, a view similar to Fig. 1, but showing slots as cut straight across the die instead of angularly disposed; Fig. 5, a sectional view similar to Fig. 2 showing a modification of the die; Fig. 6, a plan view of the die seen in Fig. 5; Fig. 7, a plan view of a blank from which either modification shown of the die member may be formed; Fig. 8, a longitudinal sectional detail drawn to a much smaller scale, showing a means for keeping the die in proper adjustment with respect to the type characters; Fig. 9, a side elevation of a check writing machine in which the invention is adapted to be used; Fig. 10, a fragmentary portion of the type support showing in plan view a line of type; Fig. 11, a longitudinal sectional view of a portion of the die member shown in Fig. 2 with correspondingly conformed type in operative engagement therewith; Fig. 12, a similar sectional view of the die member shown in Fig. 5 and of correspondingly conformed type, such parts being shown just at the commencement of the printing operation and with material, as paper, to be printed on placed between them, while Figs. 13 and 14 illustrate the appearance of the face and re-

verse sides, respectively, of a check when printed. All of the figures with the exception of 8 and 9 are drawn to a greatly enlarged scale.

5 Similar reference characters refer to similar parts throughout the several views.

Referring first to Fig. 9. At 1 is seen the base and at 2 the head of a check writing machine of the character for which the invention is more especially intended, the front portion of the head being spaced apart from the base to receive a check 31 therebetween which is supported on the plate 3. In this machine the type bars 4 extend longitudinally of and are carried on the periphery of a cylinder 5 rotatably supported in bearings 6 slideable in vertically extending guideways 7 in the side walls of the head member 2. This cylinder may be turned to bring any predetermined line of type directly above the platen or die 8 supported in the member 9, forming an integral part of the base 1, and it is raised and lowered by the toggle levers 10 and 11 on actuation of the operating lever 12. At 13 are seen the usual ink rollers mounted in suitable supporting arms 14 and held in yielding engagement with the type wheel 5 for supplying ink to the characters on the several type bars.

In Fig. 7 there is shown a blank which, when folded along the dotted lines *a*, *b*, *c* and *d*, will form a rectangular shell having parallel side and end walls 15 and 16, respectively, a top wall 17 and an open bottom. The top wall 17 is thereafter perforated by having, preferably, a series of equally spaced parallel slots cut across it, either straight, as shown in Fig. 4, or diagonally, as in Figs. 1 and 6, and when thus cut will comprise a series of equally spaced bars. These bars may be formed, as at 18 in Figs. 1, 2, 3, 4 and 11, with straight sides and, preferably, rounded outer edges, or with tapering sides and sharp cutting edges, as seen at 19 in Figs. 5, 6 and 12. An ink pad 20 of suitable material, as felt, is inserted in the shell in contact with the inner edges of the cross bars, after which the shell is placed over the reduced upper portion of a block member 21 and held thereon by pins 22 extending through both members. These two members, when assembled, comprise the sub-inking die 8 which is then seated in a slot 23, therefor in the supporting member 9 forming an integral part of the base 1 of the machine.

Any preferred means for adjusting the die both longitudinally and vertically may be provided as, for instance, that shown in Fig. 8, wherein 24 is a screw extending longitudinally of the slot 23 and threaded into a hole 25 therefor in the block member 21, such screw having a shoulder 26 engaging in a transverse slot 27 in the support 9,

whereby turning the screw causes a longitudinal movement of the die; and a vertical adjustment is provided for by the screws 28 extending upwardly through the support 9 and engaging the bottom of the block 21, 70 while the die is normally held against displacement by the centrally disposed screw 29 extending vertically through the support 9 and threaded into a hole 30 therefor in the block member 21. 75

The impressing members are type characters made either of hard metal with the face thereof serrated, as will be hereafter described, or, if preferable, of a comparatively soft composition into which impressions of the bars forming the top of the die member will be made by contact therewith under sufficient pressure, the function of the type being to both print on the face of the paper and to force portions thereof through the perforations in the die into contact with the ink pad 20, the result being an inking of the impressed characters on both sides of the paper. 80

The type characters 32 shown in the drawings are formed on bars 4 extending longitudinally of and secured on the periphery of the cylinder or wheel 5. Parallel grooves are formed in the type of a depth less than the thickness of the bars above the surface 95 of the wheel and so disposed as to register with the bars forming the top of the die. It will thus be seen that the type characters will have ridges alternating with the grooves and it is preferable that these ridges be formed with sharp cutting edges in order that the type will cut or break the paper when forcing it through the slots in the die plate. In Fig. 11 the grooves formed in the type characters have flat bottoms to receive the blunt outer edges of the die bars 18, while in Fig. 12 the grooves are the counterpart of the V-shaped die bars 19, the ridges on the type in both instances having sharp cutting edges. 100 105 110

When employing my invention the cooperation of the type and sub-inking die member will be such as to impress the characters into the paper in a manner to break the fibers, and, also, to ink such characters on both the face and reverse sides of the paper, as shown in Figs. 13 and 14, respectively. As before stated, the pad 20 will be suitably inked before inserted to place but will not at any time become dry as sufficient ink will be applied thereto from the ridges of the type characters when cutting or breaking through the paper during the printing operation. 115 120 125

It is believed that, from the foregoing description, the construction, purpose and manner of using the invention are sufficiently clear to call for no further explanation.

What I claim is:

1. In a printing machine of the character 130

described, two die members movable relatively toward each other to impress a check held between them, one of said members comprising type characters having projecting portions and the other having perforations to receive said projections, means for applying ink to said type characters for printing on the face of the check, and means under the other of said members for inking 10 on the under side of the check portions thereof forced through said perforations.

2. In a printing machine of the character described, two die members one of which is stationary and the other movable to impress 15 a check held between the two, one of said members comprising type characters having projecting portions and the other having perforations to receive said projections, means for applying ink to said type characters for printing on the face of the check, and means under the other of said members for inking on the under side of the check portions thereof forced through said perforations.

25 3. In a printing machine of the character described, a die member having perforations therethrough, a type support having a plurality of lines of type characters thereon and means for moving such support to bring a 30 selected line of type into operative position, said type characters having projecting portions adapted to engage through said perforations, means for moving said die and the selected type characters relatively to 35 ward each other to impress a check held between them, means for applying ink to said type characters for printing on the face of the check, and means under the die member for inking on the under side of the check 40 portions thereof forced through said perforations.

4. In a printing machine of the character described, an adjustably supported die member having perforations therethrough, a 45 type support having a plurality of lines of type characters thereon and means for moving such support to bring a selected line of type into operative position, said type characters having projecting portions adapted to engage through said perforations, means for moving said die and the selected type characters relatively toward each other to impress a check held between them, means for applying ink to said type characters for printing on the face of the check, and means under the die member for inking on the 50 under side of the check portions thereof forced through said perforations.

5. In a printing machine of the character described, a die member having perforations therethrough and a support for such member, a type support having a plurality of lines of type characters thereon and means for moving such support to bring a selected 65 line of type into operative position, the type

support being the movable member in the printing operation and said type characters having projecting portions adapted to engage through said perforations, means for applying ink to said type characters for 70 printing on the face of the check, and means under the die member for inking on the under side of the check portions thereof forced through said perforations.

6. In a printing machine, the combination with type characters of a die plate slotted to form a plurality of equally spaced bars, a support for said plate, and an ink pad supported against said bars on the side of the plate opposite that engaged by said 75 type characters.

7. In a printing machine, the combination with type characters of a die plate slotted to form a plurality of equally spaced and angularly disposed bars, a support for 80 said plate, and an ink pad supported against said bars on the side of the plate opposite that engaged by said type characters.

8. In a printing machine, the combination with type characters of a die plate 85 slotted to form a plurality of equally spaced bars having rounded outer edges and straight sides, a support for said plate, and an ink pad supported against said bars on the side of the plate opposite that engaged 90 by said type characters.

9. In a printing machine, the combination with type characters of a die member comprising a casing having a face plate and side walls, said plate being slotted to form 100 a plurality of equally spaced bars, a support for said casing, and an ink pad within the casing in contact with said bars.

10. In a printing machine, the combination with type characters of a die member 105 comprising a casing having a face plate and side and end walls, said plate being slotted to form a plurality of equally spaced bars, a support for said casing, and inking means within the casing for the purpose 110 specified.

11. In a printing machine of the character described, the combination with type characters grooved to form a plurality of parallel extending ridges, of a die plate 115 slotted to form a plurality of equally spaced parallel extending bars, means for moving said type characters and said die plate relatively toward each other to impress and print on both sides a check held between them, means for inking said type characters, said ridges being conformed to enter the slots in the die plate and the grooves to receive said bars, and an ink pad held against said bars on the side thereof opposite that engaged by said type characters.

12. In a printing machine of the character described, the combination with type characters grooved to form a plurality of parallel extending ridges, or an adjustably 130

supported die plate slotted to form a plurality of equally spaced parallel extending bars, means for moving said type characters and said die plate relatively toward each other to impress and print on both sides a check held between them, means for inking said type characters, said ridges being conformed to enter the slots in the die plate and the grooves to receive said bars, and an ink pad held against said bars on the side thereof opposite that engaged by said type characters.

13. In a printing machine of the character described, the combination with type characters grooved to form a plurality of V-shaped parallel extending ridges, of a die plate slotted to form a plurality of equally spaced parallel extending bars, means for moving said type characters and said die plate relatively toward each other to impress a check held between them, means for inking said type characters, and an ink pad held against said bars on the side thereof opposite that engaged by said type characters, said ridges being adapted to enter the slots in the die plate and the grooves to re-

ceive said bars, the coöperating action of the engaging members being to print on both sides of the impressed characters and to break the fibers of the paper throughout 30 the printed surface.

14. In a printing machine of the character described, the combination with type characters grooved to form a plurality of V-shaped parallel extending ridges, of a die 35 plate slotted to form a plurality of equally spaced parallel extending bars, having parallel sides, means for moving said type characters and said die plate relatively toward each other to impress a check 40 held between them, means for inking said type characters, and an ink pad held against said bars on the side thereof opposite that engaged by said type characters, said ridges being adapted to enter the slots in 45 the die plate and the grooves to receive said bars, the coöperating action of the engaging members being to print on both sides of the impressed characters and to break the fibers of the paper throughout the 50 printed surface.

HERMAN C. WELTER.
